UNITED STATES PATENT OFFICE.

VICTOR J. SMITH, OF BURLEY, IDAHO.

BERRY OR FRUIT RECEPTACLE.

Application filed October 22, 1921. Serial No. 509,590.

To all whom it may concern:

Be it known that VICTOR J. SMITH, a citizen of the United States of America, residing at Burley, in the county of Cassia and State 5 of Idaho, has invented new and useful Improvements in Berry or Fruit Receptacles, of which the following is a specification.

The object of the invention is to provide a fruit or berry box or receptacle of simple 10 inexpensive construction adapted to be crated or otherwise packed for shipment and capable of being produced from relatively stiff paper or cardboard and of being readily assembled by the consumer, to the end that 15 the elements thereof may be shipped in a flat or knock down condition; and with these objects in view the invention consists in a construction and combination of parts of which a preferred embodiment is shown in 20 the accompanying drawings, wherein:—

Figure 1 is a perspective view of a receptacle embodying the invention.

Figures 2 and 3 are plan views of the blanks representing the elements or members comprising the receptacle.

The receptacle which obviously may be made of any preferred rectangular form and of any desired dimensions or having any preferred capacity, measured or otherwise comprises a side blank represented in detail in 30 Figure 2 and a bottom blank represented in Figure 3. The side blank consists of a central fold 10 adapted to form for example one end wall of the receptacle, intermediate 35 folds 11 adapted to form the side walls of the receptacle and terminal folds 12 which are adapted to be overlapped and constitute for example the other end wall, the central and terminal or end wall folds are provided 40 with parallel slits 10^a and 12^a forming between them straps 10^b and 12^b. The bottom blank consists of a central bottom fold 13, terminal folds 14 and tongues 15 which may be terminally reduced as shown at 15^a.

45 In assembling the receptacle the wall blank is folded so that the terminal folds are brought into overlapping relation at which time the slits 12^a are brought into registration.

The bottom blank is then fitted to the folded 50 wall blank, the terminal folds 14 thereof

resting against the inner face of the intermediate fold the wall blank and the inner face of the inner terminal fold thereof. The tongues 15 are thereafter bent over against the outer faces of the slits intermediate the 55 terminal wall blank and their extremities inserted respectively through the upper slits 10^a and 12^a and thereafter through the bottom slits, which operation disposes the straps 10^b and 12^b in spanning relation with 60 the tongues. That tongue engaging the slits 12^a in the terminal blanks is inserted behind both tongues 12^b and thus the wall blank is positively held in folded relation and the tongues passing through two slits 65 are positively held against upward displacement and thus the bottom is positively maintained in place. If need be, the terminal portions of the tongues may be upturned which will constitute hook connections with 70 the straps 10^b and 12^b.

Having described the invention, what is claimed as new and useful is:—

A receptacle for the purpose indicated comprising a wall blank having a central 75 fold, terminal folds and intermediate folds between the central and terminal folds, the central and terminal folds being formed with parallel slits providing an intermediate strap, the terminal folds being disposed in 80 overlapping relation when said wall blank is in folded position and at which time the slits in the terminal folds are disposed in registration, and a bottom blank comprising a bottom fold, terminal tongues and intermediate 85 folds between the bottom folds and the tongue, said intermediate folds being disposed against the inner faces of the central wall fold and the inner terminal fold and the tongues overhanging the 90 edges of the terminal and central folds of the wall blank and being inserted through the registering slits of the terminal folds and through the slits of the central fold so as to be spanned by the intermediate straps defined by the slits. 95

In testimony whereof he affixes his signature.

VICTOR J. SMITH.
